To all whom it may concern:

Be it known that I, JAMES L. FOLSOM, of Brooklyn, in the county of Kings and State of New York, have invented a new and original 5 Design for Carpets, of which the following is a specification.

This invention relates to a new and original design for carpets and similar fabrics; and it consists in the novel grouping and configuration of figures hereinafter more fully described.

The ground *a* is ornamented with squares arranged diagonally and at regular intervals, 15 with ornamental spaces bounded by fret-work and filled in with various diagonally-arranged geometric figures. Over this ground is a leaf and flower system, *b*, consisting of a system of

stems running loosely over the face of this design, and bearing along their length leaves in 20 running groups, and small clusters of star-shaped flowers, as shown in the photograph.

I claim—

2. The design for a carpet, consisting of the leaf and flower system *b*, substantially as shown and described.
